SELVAGED UNWOVEN ZIGZAG FABRIC

Raymond J. Southwell and Theodore H. Wick-
wire, Jr., New York, N. Y.

Application August 12, 1933, Serial No. 684,800

12 Claims. (Cl. 189—82)

Our invention consists of a new article of manufacture, namely, an unwoven zig-zag fabric, formed from strands, preferably metallic strands such as wire, and made self-sustaining by the strands being secured together at their meeting surfaces, as by electric welding.

The main object of the present invention is the provision of unwoven, zig-zag, sheet fabric having a substantially continuous selvage along the edge or edges thereof.

Figure 1 of the accompanying drawing shows a fabric sheet having a substantially continuous selvage in accordance with our invention, the particular fabric shown for illustration having a square diamond mesh, except at the selvage edges, where the mesh formation is substantially triangular, and in which the selvage is a single selvage, that is, made up of single portions of wire.

Figure 2 is a similar, but fragmentary and diagrammatical, view on an enlarged scale showing a modified form with double selvage.

In making square diamond mesh fabric with a single selvage, as illustrated in Fig. 1, a set of laterally spaced continuous strands, *a*, *b*, *c*, *d*, *e*, *f*, *g*, *h*, *i*, and *j* (wire *a*—though ordinarily no different from the others—being shaded in the drawing for ready identification; and ten wires being shown for simplicity of illustration, though, ordinarily, the number is much greater), have parallel portions *a1*, *b1*, *c1*, . . . *j1*, disposed at an angle of 45° to the lengthwise direction of the desired sheet to be formed, and laid to an edge 10 of such sheet 12. There, short portions *a2*, *b2*, *c2*, . . . *j2* are disposed lengthwise of the sheet along the edge thereof to constitute or form, when secured together, a continuous, preferably straight or substantially straight, selvage, indicated generally by reference character 14. The length of each of such portions *a2* . . . *j2*, as shown, is equal to the pitch of the fabric mesh, the term pitch being used to designate the distance *p* between successive strands, as *a*, *b*, *c*, etc., measured in the lengthwise direction of the sheet. Thus, when the dispositions or lays *a1* . . . *j1*, and the dispositions or lays *a2* . . . *j2* have been made, wire *a* has caught up to or overtaken wire *b* at 15, wire *b* has similarly overtaken wire *c* at 15', and so on successively, and the portions *a2*, *b2*, *c2* . . . *j2* overlap at 15, 15' etc., and are adapted upon such overlaps being welded together, to form a selvage that is substantially straight, but still has enough kink effect in it to allow for expansion and contraction due to heat and cold in outdoor uses,

as, for fencing, and which heretofore have had to be taken care of ordinarily by the crimping of selvage wires.

Thence, portions *a3*, *b3*, *c3* . . . *j3* are laid or folded inwardly upon the lay or fold *a1*, *b1*, *c1* . . . *j1* at right angles to said portions *a1*, *b1*, *c1* . . . *j1*, (angle of 45° to longitudinal sheet direction) to the opposite edge 18 of the sheet 12. Here, again, pitch-length portions *a4*, *b4*, *c4* . . . *j4* are disposed longitudinally of the sheet 10 along the edge to form a selvage 20, similarly to formation of selvage 14. Thence, strand portions *a5*, *b5*, *c5* . . . *j5* are laid or folded inwardly upon the lay or fold portions *a3* . . . *j3* as before, overlapping substantially half of such lay or fold *a3* . . . *j3*, and this formation is recurrent being repeated to and at the respective edges indefinitely. It will be seen that in this way the portion *a5* of wire *a* (at one edge of the set of wires) comes out to the edge at 22, one pitch-length *p* ahead of point 24 where portion *j1* of wire *j* (at the other edge of the set of wires) comes out to the edge, and thus in correct position to make the spacing uniform throughout the sheet and to form an overlap with selvage 20 portion *j2* of such wire *j*.

The width of square mesh selvaged fabric made in the manner described from the set of ten continuous wires *a* . . . *j* is four times the pitch length *p*, as shown, the transverse and longitudinal pitch distances *p1*, *p* being equal with square mesh fabric, each being a diagonal of the same square; and, generally, the number of wires required for making such a square mesh selvaged fabric is 2 plus twice the quotient obtained when the sheet width is divided by the pitch.

While an exact square mesh fabric has been described in detail in order to give a full disclosure of a preferred embodiment of the invention, and is preferred, it will be understood that by choosing the transverse and longitudinal pitches of unequal length, the diamonds of the mesh may be correspondingly elongated or shortened to some extent transversely or longitudinally of the fabric. Preferably, the longitudinal pitch is at least equal to the transverse pitch.

By making the selvage forming portions of length that is a multiple of the longitudinal pitch, as twice the pitch length, and providing the necessary additional wires in the set, double thick selvage or even heavier stronger selvages can be formed, if desired, but a single selvage, as shown, is sufficient for ordinary uses. Such double-thick selvage is shown in Fig. 2, the selvage-

forming portions A2, B2, C2, etc. being of double length P or twice the pitch length p, as indicated specifically in the drawing at B2.

In making fabric of wire, the wire crossings 26 making up the interior or diamond shaped meshes 28 are preferably welded while the fabric is held by the edges by means of fingers or hooks (not shown), and after these crossings 26 have been welded with the fabric so supported, the edges 10 of the welded-together fabric are released from such hooks or fingers, and then the selvage and the substantially triangular edge meshes 30 are completed by welding the selvage overlaps together.

15 It will be seen that, by the present invention, the fabric is provided with a substantial selvage in a very simple and inexpensive manner, and without need for welding on separate wires or resorting to like expedients.

20 Having thus described our invention, what we claim and desire to secure by Letters Patent is:

1. As a new article of manufacture, zig-zag, unwoven sheet fabric which is of diamond mesh formation, except at the edges where the mesh formation is substantially triangular, and having substantially continuous straight selvage edges, 25 said fabric consisting of a single set of continuous laterally spaced strands laid to an edge of the sheet, there having selvage-forming portions disposed for a distance longitudinally along such edge, thence laid or folded 30 inwardly to the opposite edge, and there disposed along the edge of the sheet and thence laid or folded back in the same way as disposed and laid or folded at and from the first edge, with each successive lay or fold at the same face of and 35 overlapping substantially half the area of the preceding lay or fold, and said fabric and selvage being made self-sustaining and strong by the metallic strands being welded together at points of crossing and of selvage portion overlaps.

2. Fabric in accordance with claim 1, and in which the longitudinal pitch is at least equal to the transverse pitch.

45 3. Fabric in accordance with claim 1, and in which the diamond mesh is substantially square, and the number of strands in the set is 2 plus twice the quotient obtained when the sheet width is divided by the pitch (diagonal of the mesh square).

50 4. Fabric in accordance with claim 1, and in which the longitudinally disposed selvage-forming portions overlap only the next adjacent strand of the set and form principally single thickness selvage.

55 5. Fabric in accordance with claim 1, and in which the longitudinally disposed selvage-forming portions overlap the next adjacent strand

of the set and also one additional strand and form substantially double thickness selvage.

6. Fabric in accordance with claim 1, and in which the diamond mesh is substantially square, and the number of strands in the set is 2 plus twice the product obtained when the sheet width is divided by the pitch, and the longitudinally disposed selvage portions overlap only the next adjacent strand of the set and form principally single-thickness selvage.

7. As a new article of manufacture, zig-zag, unwoven sheet fabric, which is of diamond mesh formation, except at the edges, where the mesh formation is substantially triangular, and having substantially continuous straight selvage edges, 15 said fabric consisting of a single set of continuous laterally spaced metallic strands laid to an edge of the sheet and having selvage forming portions thereof disposed for a distance longitudinally along such edge, thence laid or folded 20 inwardly to the opposite edge, and there disposed along the edge of the sheet and thence laid or folded back in the same way as disposed and laid or folded at and from the first edge, with each successive lay or fold at the same face of and 25 overlapping substantially half the area of the preceding lay or fold, and said fabric and selvage being made self-sustaining and strong by the metallic strands being welded together at points of crossing and of selvage portion overlaps.

30 8. Fabric in accordance with claim 7, and in which the longitudinal pitch is at least equal to the transverse pitch.

9. Fabric in accordance with claim 7, and in which the diamond mesh is substantially square, 35 and the number of strands in the set is 2 plus twice the quotient obtained when the sheet width is divided by the pitch (diagonal of the mesh square).

10. Fabric in accordance with claim 7, and in 40 which the longitudinally disposed selvage-forming portions overlap only the next adjacent strand of the set and form principally single thickness selvage.

11. Fabric in accordance with claim 7, and in 45 which the longitudinally disposed selvage-forming portions overlap the next adjacent strand of the set and also one additional strand and form substantially double thickness selvage.

12. Fabric in accordance with claim 7, and in 50 which the diamond mesh is substantially square, and the number of strands in the set is 2 plus twice the product obtained when the sheet width is divided by the pitch, and the longitudinally disposed selvage portions overlap only the next adjacent strand of the set and form principally single-thickness selvage.
